United States Patent Office

Des. 229,138
Patented Nov. 13, 1973

229,138

SOAP DISH

Delmas E. Collins, West Lafayette, Ohio, assignor to
Jones-Zylon, Inc., West Lafayette, Ohio

Filed May 4, 1972, Ser. No. 250,464

Term of patent 14 years

Int. Cl. D6—06

U.S. Cl. D6—89

FIG.1

FIG.2

FIG.3

FIG.4

FIG.5

FIG. 1 is a top plan view of a soap dish showing my new design;

FIG. 2 is a front elevation thereof;

FIG. 3 is a bottom plan view thereof;

FIG. 4 is a rear elevation thereof;

FIG. 5 is a side elevation thereof, the opposite side being a mirror image of the side shown.

I claim:

The ornamental design for a soap dish, as shown and described.
